(57) **CLAIM**

The ornamental design for sparring protective equipment, as shown and described.

DESCRIPTION

FIG. 1 is a front elevational view of sparring protective equipment, showing my new design;

FIG. 2 is a rear elevational view thereof;

FIG. 3 is a right elevational view thereof;

FIG. 4 is a left side elevational view thereof;

FIG. 5 is a top plan view of sparring protective equipment; and,

FIG. 6 is an elevational view of the glove portion of the sparring protective equipment, illustrating detail of the sewn-together fingers.

The person shown in broken lines in FIGS. 1–6 is for illustrative purposes only and forms no part of the claimed design. The dotted lines on the glove in FIG. 6 illustrate stitching holding the glove fingers together.
